Patented Aug. 6, 1963

195,910

COMBINED SLIDE PROJECTOR AND SLIDE TRAY

Richard J. Olson, Lima, and Frank A. Zagara, Rochester,
N.Y., assignors to Eastman Kodak Company, Rochester,
N.Y., a corporation of New Jersey

Filed Dec. 22, 1961, Ser. No. 68,028

Term of patent 14 years

(Cl. D61—1)

Fig. 2

Fig. 3

FIG. 1 is a front perspective view of a combined slide projector and slide tray, showing our new design;

FIG. 2 is an elevational view of the side opposite that shown in FIG. 1;

FIG. 3 is a rear elevational view; and

FIGS. 4 and 5 are sectional details taken substantially on lines 4—4 and 5—5, respectively, of FIG. 3.

The bottom, not shown, is conventional.

We claim:

The ornamental design for a combined slide projector and slide tray, as shown and described.
